(57) CLAIM

The ornamental design for a tent as shown and described.

DESCRIPTION

FIG. 1 is a front elevational view of a tent showing my new design;

FIG. 2 is a rear elevational view thereof;

FIG. 3 is an enlarged left side view thereof;

FIG. 4 is an enlarged right side view thereof;

FIG. 5 is a top plan view thereof; and,

FIG. 6 is a left, rear perspective view thereof.

The broken lines illustrate portions of the tent that do not form part of the claimed design.
